ASSOCIATES; Arlyn Alonzo

(57) **CLAIM**

The ornamental design for an earbud, as shown and described.

DESCRIPTION

FIG. 1 is a perspective view of an earbud showing the new design.

FIG. 2 is a front view thereof.

FIG. 3 is a back view thereof.

FIG. 4 is a left view thereof.

FIG. 5 is a right view thereof.

FIG. 6 is a bottom view thereof; and,

FIG. 7 is a top view thereof.

1 Claim, 4 Drawing Sheets
